Des. 204,337
Patented Apr. 5, 1966

204,337

COMBINED PAPER CLIP AND CALENDAR

Stanley A. Smith, Minneapolis, Minn., assignor to Standard Packaging Corporation, New York, N.Y., a corporation of Virginia

Filed Nov. 2, 1964, Ser. No. 82,416

Term of patent 3½ years

(Cl. D74—2)

FIG. 1

FIG. 2

FIG. 3

I claim:

The ornamental design for a combined paper clip and calendar, as shown and described.
